United States Patent Office.

ROBERT ATKIN, OF BROOKLYN, NEW YORK.

Letters Patent No. 79,183, dated June 23, 1868.

IMPROVEMENT IN PROPELLERS.

The Schedule referred to in these Letters Patent and making part of the same.

TO ALL WHOM IT MAY CONCERN:

Be it known that I, ROBERT ATKIN, of Brooklyn, in the county of Kings, and State of New York, have invented certain new and useful Improvements in Propelling Vessels; and I do hereby declare that the following is a full, clear, and exact description thereof, which will enable others skilled in the art to make and use the same, reference being had to the accompanying drawings, forming a part of this specification, in which—

Figure 1 is a plan view of my invention, when the propeller is operated by a chain-belt, or its equivalent, the view being taken from a section through fig. 3.

Figure 2 is a similar view, when an eccentric-rod and crank are employed.

Figure 3 is a side view of the invention, taken from fig. 1.

Figure 4 is a side view of the invention, when the propeller is raised from the water.

Similar letters of reference indicate corresponding parts.

This invention relates to certain improvements in the method of propelling vessels, chiefly intended to be used as an auxiliary power to sailing-vessels.

I propose to apply to the sides of the vessels (at that part where paddle-wheels are usually placed,) screw-propellers, which are set in bearings in frames hinged or jointed to the sides of the vessel, and capable of being raised or lowered from the bulwarks by means of lifting or suspending-chains, worked by a windlass or other equivalent gear. The frames are also held by supporting-chains from the bulwarks, the lifting-chains being hung from the davits. The frames contain screws or propellers, driven by endless chains, and whelped bosses on the shafts; or the shafts may be actuated by toothed gearing, in either case worked by steam-power, the chains or shafts passing through the sides of the vessel. One or more screws may be placed on each side of the vessel, and by reversing the engine on one side, and going ahead on the other, the vessel may be turned round in a space little more than her own length. By placing the propellers amidships, and on each side of the vessel, the vibration incident to the use of the screw-propeller is reduced very considerably, and an economy of space will be effected. When the wind is fair the propellers may be raised from the water, and the use of the steam-power be discontinued.

As I propose to employ, for the purpose of working the auxiliary screw-propellers, steam-engines of but small size and little weight, running at a suitably high speed, so as to actuate the propellers as directly as possible, and without the intervention of heavy, expensive, and complex gearing, I am, by the arrangement and disposition of parts of the machinery and gearing herein described and illustrated, enabled to contrive and utilize, in the same engines, several functions besides that of engines for propulsion (as auxiliary engines) whilst at sea, when in a calm, or with light or adverse winds, those of actuating steam-winches, steam-cranes, steam-derrick gear, or other forms of steam-apparatus for loading or unloading cargo; also for actuating fire-engines, or other water-pumping apparatus, and performing other work in and about a ship.

In the accompanying drawings, I have merely shown the general character of the auxiliary propelling-apparatus, and the principal features thereof, without attempting to elaborate the plans or means for actuating or giving motion to the propelling-apparatus, or showing the various modes of construction and arrangements of parts, which it might be requisite or necessary to adopt to suit the particular requirements of each ship, or the existing arrangements of her bulk-heads, or her internal construction or fittings, but in every case, whilst the power and disposition of the steam-engines or boilers, and gearing for actuating the propellers, are to be primarily determined with reference to the auxiliary propulsion of the ship.

The further object which I seek to carry out, when putting my invention into practical use, is to so arrange and dispose the motive-power apparatus as to utilize it for other purposes, as hereinbefore stated.

The several figures show the mode of applying the apparatus in accordance with my invention, wherein the iron framing containing a screw-propeller is shown as hinged to the ship's side, and suspended from a davit by means of a suitable tackle, rotary motion being given to the screw-propeller by means of an endless chain passing over a pitch-wheel within board, and a corresponding wheel upon the axis or short shaft of the screw.

The screw is mounted between the jaws of the hinged frame, and suitable collars and bosses are provided, for receiving and resisting the thrust of the screw. The frame is capable of being raised out of the water by means of the davit-tackle, so that when the ship is required to be under canvas alone, the frame and screw being raised, offer no impediment to the ship's sailing.

In the several views, A is the ship; B, the screw-propeller; C, the frame; D, the chain-wheel, fitted upon the screw-propeller; E, the endless chain; F, the chain-wheel, fitted within the ship, by means of which motion is transmitted to the screw-propeller whilst in use. A boxing, G, is shown, in which the chain-wheel connected with the motive-power is fitted, and by means of which boxing the openings left in the side of the ship for the passage of the chain are enclosed. H is an "iron bow," for connecting the chain or rope from the davit to the hinged frame; I is the suspending-rope or chain, and K the davit.

Motion may be given to the propeller fitted in each side of the ship, by means of separate and independent steam-engines, moving at a suitably high speed, and operating the chain-pulley contained within the boxing or water-tight casing, directly, by means of a crank at each end of the pulley-shaft, each crank being set at a proper angle, and the diameters of the two chain-pulleys may be of different sizes, to give the requisite speed to the propeller.

Instead of mounting two small vertical or angularly-placed steam-engines, one on each side of the boxing G, a pair of small engines may be fitted to the ship's side, or under or on the deck, and the double crank-shaft thereof be coupled to the end of the chain-pulley shaft, projecting on one side through the boxing.

When found to be more convenient, one pair of engines, of larger size and power, may be placed between the port and starboard propellers, and the motion thereof be communicated, either by means of shafts and wheel-gearing, or by chains and chain-wheels. Instead of employing chain-wheels and endless pitch or other forms of chains for connecting the inboard gearing with the overhanging screw-propeller, for the purpose of rotating it, wheel-gearing and shafting may be substituted.

The hinged frames for containing the screw-propellers, instead of being of the form and construction shown in the various figures of the accompanying drawing, and mounted or hung from the side of the vessel, as therein shown, may be so formed as to arch over from the ship's sides, (instead of projecting therefrom in a straight or nearly straight line,) and so admit of any desired arrangement of staying or trussing, without interfering, by the exposed surface thereof, with the motion of the ship through the water whilst under steam.

By preference, I propose to place the steam-engines and boilers as near as may be convenient to the propellers placed on each side of the vessel amidships, as thereby the various mechanical contrivances for cargo-working, pumping, capstan and windlass-working, and other purposes, may be more readily connected, set in motion, and worked, so that when the steam-engines are not required to be solely or entirely employed in propelling, they may be used for other purposes whilst at sea, and when the ship is in harbour the engines may be employed for cargo-moving and other purposes.

Figs. 1, 3, and 4, exhibit the invention when the chain-belt is employed for connecting the propeller with the inboard-wheel F, but at fig. 2 the propeller-shaft is formed with a crank, a, and is driven by a connecting-rod, b, having a hoop, c, which fits in an eccentric, d, the centre of the shaft e of the said eccentric being coincident with the centre upon which the hinged frame C vibrates, so that it will be possible to raise or lower the propeller while connected by a rigid rod.

The shaft e is provided with a crank, f, by which it is connected with the power in the ship, or for the crank a belt-wheel or pulley or toothed wheel may be substituted, as will be obvious.

I claim as new, and desire to secure by Letters Patent—

The application of the helical propellers B B to the sides of a vessel, by means of a hinged frame, C C, in combination with a suitable mechanism for actuating said propellers, the latter having no connection with the vessel below the water-line, and the entire apparatus being made capable of being elevated and turned up against the side of the vessel, and out of water when not required for use, substantially as and for the purpose specified.

The above specification of my invention signed by me, this 9th day of March, 1868.

ROBERT ATKIN.
